DESIGN FOR A COMBINED LENS AND ASH TRAY

George M. Cressaty, New York, N. Y.

Application August 23, 1944, Serial No. 114,991

Term of patent 14 years

(Cl. D48—1)

To all whom it may concern:

Be it known that I, George M. Cressaty, a citizen of France, residing in New York, in the county of New York and State of New York, have invented a new, original, and ornamental Design for a Combined Lens and Ash Tray, of which the following is a specification, reference being had to the accompanying drawing, forming part thereof.

Fig. 1 is a top plan view of a combined lens and ash tray showing my new design;

Fig. 2 is a bottom plan view thereof; and

Fig. 3 is a sectional view on the line 3—3 of Fig. 1.

I claim:

The ornamental design for a combined lens and ash tray, substantially as shown.

GEORGE M. CRESSATY.
